ALLAN F. JACOBSON, OF NEW YORK, N. Y.

DEVICE FOR CONTROLLING THE SPEED OF TRAINS.

1,288,602.

Specification of Letters Patent. Patented Dec. 24, 1918.

Application filed January 28, 1914. Serial No. 814,874. Renewed May 10, 1918. Serial No. 233,787.

To all whom it may concern:

Be it known that I, ALLAN F. JACOBSON, a citizen of the United States, and resident of borough of Richmond, county of Richmond, 5 city and State of New York, have invented certain new and useful Improvements in Devices for Controlling the Speed of Trains, of which the following is a specification.

The device, the subject of this invention 10 is a further development and improvement in an art that has been made the subject of previous applications by myself and others.

In the earlier inventions certain difficulties have been experienced in accomplishing 15 by the devices and means supplied all of the separate requirements that are demanded of a complete and highly efficient train stop, or controlling mechanism, and I have therefore endeavored to fulfil these requirements in a 20 manner at once simple and efficient. I have arranged for a selective operation and for a multiple operation, both of which are as simple as they will no doubt appear now that they have been developed and shown 25 possible. The construction and method of operation will be fully set forth as the specification progresses.

The following is what I consider the best means of carrying out this invention.

30 The accompanying drawing shows in diagram and in central vertical section my completed device. In connection with this drawing it will be understood that no attempt has been made to show the parts in operative position nor are the separate elements drawn to any particular scale, it being considered more essential that the construction of novel features be shown in combination with a wiring diagram for the electrical connections that will be readily understood by any one familiar with the art.

At 1, and 2 I have shown ordinary rails of any preferable material and these rails combined may be considered as composing 45 an ordinary track over which steam or electric locomotives are free to operate. The air gaps α in the rail 2, indicate the breaks or insulated sections between blocks. At a convenient point between the rails 1 and 2 50 I have arranged a third rail 3 which may be a bar of metal or any other similar and convenient member. This third rail is also divided into sections as is indicated at α .

In operative relation to the track I have 55 shown the track signals 4 properly connected by means of signal circuits 5 and these sig-

nals may be arranged to operate in any ordinary manner common to block signals. I have however made certain additional connections that are here shown and that will 60 at the proper time be fully described.

At 6 I show a generator of sufficient capacity and of any desirable voltage which may be driven by an independent turbine or by any other satisfactory means directly 65 from the boiler or other source of power. The current generated by the dynamo or generator 6 is passed through the circuit breakers 7 and 8 into the solenoid coils 9 and 10 and when these coils are energized 70 they will lift the cores 11 and 12 which in turn may be caused to operate an auxiliary steam valve or electric switch as desired.

Thus far I have set forth only a general idea of the operation. I will now carefully 75 canvass each and every step so that the full value and importance of each part may be fully understood and I will consider for the purpose of this canvass that the locomotive used is an ordinary steam locomotive, that 80 the road bed and block signal arrangement are of any well known and satisfactory type and that where two or more locomotives are mentioned they will each be steam driven and each will operate under ordinary conditions and requirements.

Entering one of the upper cylinders 13 I have shown a pipe 14 which is connected to the train line air pipe and I desire that the connection should be so made that when the 90 air valve is open or closed this pipe 14 and the pressure therein will be subject only to the control of that valve; in other words, this pipe 14 should be connected directly with the break operating pipes and no means should 95 be provided for controlling the pressure in this pipe alone. When an engineer desires to start his locomotive he will first see that the generator 6 is in operation for unless the coils 9 and 10 are charged steam cannot be 100 admitted to the throttle. The plungers 11 and 12 will remain down retaining the auxiliary steam valve in a closed position, at the same time the brakes cannot be released because the pressure of air normally used to 105 release the brakes will be exhausted by passing through the pipe 14 into the lower portion of the cylinder 13 and outward through the passage 15. If, however the plunger or core 11 is lifted the passage 15 will be closed 110 by reason of the port 16 in the rod 17 passing out of register with the passage 15. This

movement of the rod 17 occasioned by the operation of the solenoid 9 will not only allow the brakes to be released but will also allow steam to pass to the throttle of the engine although to a limited extent. When however the piston 18 has been lifted past the port 19 the air entering through the pipe 14 will be free to pass under the piston 20 in the cylinder 21 and this piston will be raised, that is provided the circuit through the solenoid 10 has been completed and the port 22 in the rod 23 has been lifted out of register with the passage 24. The operation of the air pressure and the energizing of the solenoids 9 and 10 will then combine to lift the pistons 18 and 20 upward to their fullest extent even against the pressure of the springs 25 and 26 and the full head of steam being received by the engine it can proceed at a speed that shall be determined by the engineer.

The running positions of the circuit breakers 7 and 8 are shown in full lines on each circuit breaker and if when in that position the locomotive enters a green or controlled block the circuit breaker 8 will be automatically thrown into the position shown in dotted lines and the solenoid 10 will be de-energized. Its plunger will at once drop because of the force of the spring 26 and the steam pressure will be reduced. When the piston has dropped to its full extent, the port 22 will be opened, and the air may escape at a rate that may be predetermined either by the size of the passage 24, or by a suitable valve that may be inserted into this passage.

It is not intended however that the air shall escape from this passage with sufficient freedom to apply the brakes. Now should the locomotive pass into a white or free block or should the green or controlled block be changed to white, the circuit breaker 8, which is a balanced breaker will be automatically re-set, and the solenoid 10 reenergized with the result that the locomotive will again receive its full head of steam.

Should the locomotive however run into a red or stop block both circuit breakers will be opened or thrown to the position shown in dotted lines, both solenoids will be deenergized and both plungers 11 and 12 will drop shutting off the steam and later exhausting the air from the train line air pipe and setting the brakes in the usual manner.

The operation of the circuit breakers is occasioned by an overload being thrown upon them. The overload upon the green or controlled circuit is determined by a resistance 27 which is so adjusted that it will not allow sufficient current to pass to operate the red or circuit breaker 7, both circuit breakers however are operated by a short circuit through the switch 28 which is controlled by the red signal.

Thus far I have described the mechanical

construction and operation of my device, but now I will set forth the path of the current during its several operations using reference letters to indicate the several electrical connections. I may sometimes refer to the connections or wires merely by their letter and in this instance it will be understood that a wire is intended, as coils, circuit breakers and other mechanical devices will be referred to by their proper names.

We will first consider what will be termed the white indication or the normal running condition of the train. The path of the current will, under this condition be as follows: from the generator 6 to A to B through the coils 9 to C to D to the center right hand terminal of the circuit breaker 7, through the bar of the circuit breaker to the lower right hand terminal of the circuit breaker, to E to the coil F to G back to the generator 6. The coil 10 is in circuit through A' through the switch coil H, through the circuit breaker 8, through I to J to the coil, back through K to L to the upper right hand terminal of the circuit breaker 7 to the bar thereof, to E, F, and G and back to the generator. The white light of the signal 50 is energized from M which is connected to I to J to N to the circuit breaker 7 to E, F and G.

When a short circuit through the resistance 27 occurs, it will throw an overload on the coil H of the switch H', opening this switch and at the same time releasing the circuit breaker 8 allowing it to assume the position indicated by dotted lines. At this time the coil 10 will also be cut out. This condition is what may be termed the green signal. When the green signal is illuminated the path of the current will be as follows: from the generator to A to B; through the coil 9 to C to D; through the center and lower right hand terminals of the circuit breakers 7 to F to G. The current will also pass through A', through the coil H to the right hand upper terminal of the circuit breaker 8; to the center rail; across the partial short circuit to the circuit breaker 7, to D, E, to F, to G, to the generator. The current will also pass from the lower right hand terminal of the circuit breaker 8 to O, to P, through the brake 31, through the contactor 39; through the wire Q through the resistance R, to the circuit breaker 7, back to the generator. The green signal will be illuminated by the course of the current from P to S, through the green light to the circuit breaker 7. Now should a complete short circuit occur at this time or any other time, both coils 9 and 10 will be cut out, the brake will be applied with full force, and the path of the current will be from A to A' through the coil H to the upper right hand terminal of the circuit breaker 8 to T across the short circuit between the intermediate and outside rails to D through the arm of

- the circuit breaker 7 to E, to the coil F to G, and return to the generator. The brake will be applied through the lower right hand terminal of the circuit breaker 8 which receives 5 its current through A, A' and H, to O, P, the brake 31, through the contact disk 39, through Q, through the lower left hand and center terminals of the circuit breaker 7 to the coil F to G, to the generator.
- 10 It will be noted however that immediately the short circuit occurs the arm of the circuit breaker 7 will be thrown into the position of the dotted line, this will open the short circuit by disconnecting the center and lower 15 right hand terminals of the circuit breaker 7 but will maintain the brake in a set condition through the left hand side of the circuit breaker as described.
- 15 It may sometimes be desirable to allow a locomotive to enter a red block at a reduced speed and to accomplish this I have arranged a switch 29 which may be located on the signal bridge or pole and which may be operated only by means of a key normally in the 20 possession of a flag man. When this switch 29 is open the conditions of operation are similar to those described in connection with a green signal, that is, a complete short circuit between the rails cannot occur as the 25 resistance 30 will offer a path of less resistance then would a short circuit, but in this instance the resistance 30 is used in lieu of the resistance 27. I prefer that this switch 29 should be entirely inclosed and that it 30 should be returned to a closed position by means of a spring or weight, so that when the key is withdrawn the switch will close and the train brought to a stop unless the red signal has been cleared.
- 35 40 It is often desirable to utilize two engines in tandem or to use one locomotive as a pusher or assistant to another. Under ordinary conditions this could not be accomplished as the first locomotive would constantly set a red signal against the second locomotive thereby operating the solenoids and brakes of the second locomotive and forbidding it from accomplishing any useful work. To overcome this difficulty I have 45 provided a means whereby the second locomotive will be under the control of the first locomotive only and even the deenergizing of its solenoids will not forbid its useful operation.
- 50 55 Through a suitable pipe I connect the train line air pipe of the first locomotive with the outlet 35 of the second locomotive and when the pressure is raised to release the brakes of the first locomotive and train 55 the air enters the cylinder 36 of the second locomotive under the piston 37 compressing the spring 38 and through the disk 39 and contacts 40 and 41 opens the circuit through the electric brake 31 on the second locomotive. At the same time the pressure of the
- air lifts the piston 42 in the cylinder 43 raising the plunger 11 and allowing the second locomotive to receive steam at its throttle and when this piston 42 is raised above the port 44 the air pressure will enter under the piston 45 raising it and the plunger 12 so that the second locomotive may receive its full steam pressure. The movement of the pistons 42 and 45 closes the ports 16 and 22 and the brakes of the second locomotive will be freed by the air pressure of the first locomotive or train line reservoir. It will be noted that this operation can take place even though both of the circuit breakers 7 and 8 are in the positions shown by the solid lines, 80 and it will further be noted that this same operation may take place in any number of locomotives that are connected together in a similar manner. The first locomotive operating the second, the second operating the third and so on. It will however be understood that only the first locomotive will be subject to the control of the track signals, but it will also be noted that a reverse or control or stop operation of the first locomotive will be accompanied by a similar operation of each of the other locomotives for the lowering of the pressure of the train line pipe from the first locomotive occasioned by the setting of the brakes will be accompanied by 95 the lowering of the pistons 42 and 45 of any following locomotive.
- 90 95 At 50, I have shown an indicator which may be placed within the cab and which will serve as a check on the operation of the track signal. This however may be omitted. At 51 I have shown a port in the cylinder 46 which will serve to relieve the pressure above the piston 45. A similar port may be provided in each cylinder or they may all be 100 omitted as desired. The switch 29, described as arranged upon a suitable pole may also be omitted and other modifications may be made within the scope of the appended claims.
- 100 105 Having carefully and fully described my invention what I claim and desire to secure by Letters Patent is:—
- 110 115 1. A device for controlling the speed of trains having in combination with a throttle valve of a locomotive a plurality of plungers, magnetic means for elevating said plungers, and resilient means for urging said plungers downward and means controlling said plungers adapted to retain one said 120 plunger after the operation of the other said plunger as herein specified.
- 120 125 2. A device of the character described comprising a steam valve and a plurality of electrically controlled plungers for operating said valve, each said plunger operating said valve through a part of its entire movement, a spring for returning each said plunger and a piston and cylinder adapted to assist in the compression of each said spring in combina- 130

tion with a source of electrical energy, and a plurality of circuit breakers for obtaining a consecutive operation of said plungers.

3. A device of the character described comprising a plurality of cylinders having pistons operable therein and a plurality of solenoids having movable cores operable therein, said cores and said pistons being adapted for simultaneous operation, means for admitting brake line air pressure under certain of said pistons, means for admitting air pressure from another locomotive under other of said pistons, and means for energizing said solenoids, the admission of air from an outside source or the energizing of said solenoids serving to check the free exhaust of air from said brake line for the purpose set forth.

4. A device of the character described comprising a steam valve, a plurality of electromagnets having movable plungers for operating said valve, a source of electrical energy for said electromagnets, a plurality of circuit breakers between said electrical source

and said electromagnets, a circuit parallel to the circuits of said electromagnets and by means of which the current flow through said circuit breakers may be increased; one said circuit breaker operating one said electromagnet to partially close said valve upon a small increase of current passing through said circuit breaker, the other said circuit breaker being adapted to operate the other said electromagnet and completely close said valve when a greater quantity of current passes through said circuit breaker, in combination with visual signals in said circuits and adapted to indicate the position of said circuit breakers and said plungers as herein specified.

Signed at New York city, in the county of New York and State of New York this 27 day of January 1914.

ALLAN F. JACOBSON.
